Irving Rossi, West Orange, N. J.

Application April 30, 1942, Serial No. 441,153

5 Claims. (Cl. 85—5)

The present invention relates to improvements in clamping devices and methods of making such devices, more particularly to devices of this type also known as skin fasteners as used, e. g., in the manufacture of airplanes and which serve as temporary rivets for assembling or clamping together perforated metal sheets and other structures preparatory to and to facilitate the riveting thereof.

In my copending application, Serial No. 384,461, filed December 21, 1941, entitled "Clamping device," and my U. S. Patent No. 2,339,881 of January 25, 1944, entitled "Skin fastener," I have described devices of this character comprising essentially a body member or support provided with a circular opening, equal in diameter to the perforations in the sheets to be clamped, and a retaining or clamping element arranged in relatively movable relation with respect to said support, said retaining element having a pair of resilient legs or prongs provided with shoulders and projecting through said opening. A spreader interposed between said prongs and arranged in relatively fixed relation to said support also projects through said opening with the combined cross-sectional area of said prongs and interposed spreader being equal to and filling said opening. Normally, the spreader holds said prongs and shoulders in retracted spaced-apart position against their natural bias by the provision of suitable spring means interposed between said spreader and retaining element and urging said prongs and shoulders towards said support to clamp a pair of sheets therebetween, while allowing said prongs and shoulders to pass beyond said spreader and be operated towards each other against the action of said spring means in such a manner as to permit of ready insertion in and withdrawal of said prongs from the aligned perforations in the sheets or other structures.

An object of the present invention is to provide a device of the above type embodying features of improvement to increase its efficiency and reliability in operation.

A further object is the provision of a skin fastener constructed in such a manner as to enable quick and ready application to and removal from the perforations in the sheets to be clamped or assembled.

Another object is to provide a fastener of the above type which while small in size will permit of applying considerable clamping pressure between a pair of perforated skin sheets sufficient to withstand the forces of a riveting operation.

Another object is to provide a fastener adapted to hold two or more perforated sheets or other structures in perfect alignment in a tight and substantially vibration-proof grip.

Still a further object is to provide a fastener which can be quickly and easily disassembled

and re-assembled to speed production and for the quick interchange of repair parts.

Still a further object is the provision of a fastener which can be safely and readily installed in and removed from the sheets to be clamped with the aid of a suitable skin fastener plier or equivalent device.

Another object is to provide a skin fastener for use in riveting operations especially in the fabrication of airplanes which will cause the perforations of two or more superposed plates or sheets to become readily aligned during the insertion of the fastener and which will cause the fastener to be firmly locked against the edges of the perforations in the inserted or clamping position to insure a firm connection and vibration-free grip of the sheets or plates capable of withstanding the forces of a riveting operation.

Another object is to provide a fastener of improved construction and a special plier for installing and removing the same from the aligned holes to increase the operating safety and efficiency.

The above and further objects and advantages of the invention will become more apparent from the following detailed description taken with reference to the accompanying drawings forming part of this specification and wherein:

Figure 1 is a vertical cross-sectional view of a skin fastener embodying the principles of the invention; Figure 2 is a partial cross-sectional view taken on line 2—2 of Figure 1; Figure 3 is a horizontal cross-section taken on line 3—3 of Figure 2; Figure 4 is an isometric view of the spreader element forming an essential part of the fastener; Figure 5 is a partial view similar to Figure 2 showing a modification of a skin fastener according to the invention; Figure 6 is a horizontal cross-section taken on line 6—6 of Figure 5; Figure 7 is an isometric view showing the additional element provided according to Figures 5 and 6; Figure 8 is an elevational view of a fastener and improved operating plier showing the position at the end of the first stage during the insertion cycle; Figure 9 is a partial isometric view of the improved plier shown in Figure 8; Figures 10 and 11 are partial views of the upper and lower parts, respectively, of the fastener illustrating the cooperation with the improved plier; Figures 12 and 13 are partial cross-sectional views showing modified housings for fasteners suitable for use with flush rivets and counter-sunk sheets as shown in Figure 14; and Figure 15 shows another improved housing for a skin fastener in accordance with the invention.

Like reference characters identify like parts throughout the different views of the drawings.

Referring to Figures 1 to 4, the numeral 10 indicates the body member or support of my improved skin fastener which, in the example

shown, takes the shape of a cup or shell of circular cross-section provided with a flange 11 at its upper open end and having a curved or outwardly vaulted bottom 12. The latter has a central circular opening 13 having a diameter equal to the diameter of the aligned holes or perforations in a number of superposed perforated structures such as a pair of sheets A and B shown in the drawings to be temporarily assembled or clamped together.

I have further shown a clamping or retaining element 14 constituted, according to the present improvement, by a unitary resilient wire member of semi-circular or segmental cross-section bent into a U or hairpin shape to form a pair of legs or prongs with their flat surfaces facing each other as shown in Figure 3. The prongs in the example illustrated are so shaped as to comprise a pair of substantially parallel upper sections 14a adjacent to the bent portion 14d followed by intermediate sections 14b spaced at a lesser distance than sections 14a and a pair of lower or outer sections 14c having outward protuberances or shoulders 15 and being bent inwardly at an angle to an extent normally to leave a slight opening or spacing between the opposite faces of said shoulders as shown at 15' in Figure 8. This spacing is so chosen as to enable an easy insertion of the prongs and shoulders 15 through the perforations in the sheets A and B in the manner described hereinafter while providing a sufficient resiliency to cause members with slightly mis-aligned perforations to slide sufficiently to become readily aligned during the insertion of shoulders 15.

The retainer 14 in the operative position of the fastener as shown in Figure 1 projects through the perforations in the bottom 12 and in the sheets A and B and the sections 14c are forced into a more or less straight shape in such a manner as to provide a slight wedging effect or camming with the inner edges of the sheet perforations through the provision of a T-shaped spreader having a portion or extension 16 interposed between said prongs and a cross arm 17 bearing against the inner surface of the bottom 12. This camming or wedging effect in a lateral direction against the edges of the perforations forms an important feature of the present invention in that it insures the perforations in the sheets to be closed tightly, thereby holding the sheets in perfect alignment and in a tight and substantially vibration free grip. For this purpose the length of sections 14c is so designed and related to the spreader portion 16; that is, that points y at the beginning of the inward bend of sections 14b are at a predetermined distance from the upper edge of the spreader in the retracted position as shown in Figure 1 as to obtain a desired alignment and camming of the sheets without damage to or permanently deforming the same. In practice, this effect is obtained if the length of the lower bent sections 14c is of the order or somewhat less than the combined thickness of the spreader-arm 17, the bottom 12 and the sheets A and B to be clamped, or, as pointed out, if the apex y of the angle is slightly below the upper surface of the spreader or is positioned adjacent to the inner surface of the end wall 12 in the retracted position of said retainer as shown in the drawings.

The position of points y is further determined by the angle at which sections 14c have to be flexed inwardly to obtain the desired camming with the inner edges of the sheet perforations

without jamming and interference with the easy application and withdrawal of the fastener.

Since the distance between the prong sections 14b and 14c is predetermined by the size of the holes in the members A and B to be clamped, and since furthermore the size of the spring 20 is determined by the clamping pressure to be obtained between members A and B, that is requiring in most cases a spring having a diameter substantially exceeding the spacing distance between sections 14b and 14c, it is advantageous to increase the spacing between the upper prong sections 14a so as to conform to the inner diameter of the spring as shown in the drawings in order to straighten or balance the entire assembly in a manner readily understood. On the other hand, if a smaller spring of lesser diameter is sufficient the legs of prong 15 may be straight from the points y on upward and all the remaining elements like cup 10 and cap 21 may be reduced in size accordingly.

The aforementioned feature of the invention together with the employment of a sufficient clamping force provided by a coiled tension spring of adequate strength and the concentration of the pressure to a narrow edge zone near the perforations in the sheets A and B to be described presently make it possible to temporarily connect one sheet to another or any other perforated structure with a tight grip substantially without the likelihood of relative shifts or loosening of the sheets during the riveting of adjacent parts of the sheets. In the case of very thin sheets as used in airplane construction, this results in a taut skin surface free from the slightest bulge or buckling effects as heretofore experienced when using fasteners of inferior construction.

The undersurface of the spreader cross arm 17 is shaped to conform to the inside of bottom 12 to normally allow the spreader to be rotated relative to cup 10, or at least follow accidental twist exerted thereon through the prongs by the spring 20 or due to inaccuracies in the plier or other applicator and other causes. In this manner jamming or breakage of any part is avoided, while the bottom 12 cooperates with the spreader at all times in maintaining it in a predetermined relation to the cup and the holes in the member A and B, respectively.

I have furthermore shown means to relieve both the spreader and cup of excess stress exerted by the spring 20, consisting in the example shown of an inverted cupped or dished washer 18 placed over the spreader portion or cross arm 17, said washer being provided with a pair of diametrical recesses in the cylindrical part thereof adapted to receive the outer ends of said cross arm (see Figure 3). The upper or flat part of washer 18 is provided with a suitable opening or perforation for passing and guiding the prongs 14b of the retainer 14.

The upper sections 14a of the retainer 14 project beyond the shell 10 and have secured thereto a head-piece or cap 21 by the aid of a cross-pin 24 passed through diametrical bores in said cap and embracing the upper bent portion 14d of the retainer. Cap 21 is slightly tapered outwardly and provided with a curved top 22 and a lower annular recess 23 formed by a depending flange, said recess adapted to receive the upper end of a coiled tension spring to be described presently. Pin 24 is locked in position by a slit resilient ring 25 placed in a circumferential groove of the cap 21 to enable easy assembly and dis-assembly of the fastener during

manufacture and for the interchange of repair parts. The locking ring 25 is advantageously made of resilient steel wire and slit with the open ends biased away from each other to insure a tight fit and to allow of easy application to and removal from the groove in the cap 25.

A coiled tension spring 20 of suitable size encircling the retainer 14 has its upper end arranged to engage recess 23 as pointed out and has its lower end bearing against the upper surface of the washer 18 thereby resiliently restraining both the washer 18 and spreader 16, 17 against axial or longitudinal movement. Spring 20 is designed to provide a sufficient force to urge the projecting part of retainer 14 in a direction inwardly of the body or shell 10 to firmly lock shoulders 15 against the under surface of the lower skin sheet B in the operative position of the fastener as shown in the drawings, or against the outer surface of the bottom 12 in the normal or non-use condition of the device.

The dished washer 18, besides taking the thrust out of the spring 20 and relieving the shell 10, has the further advantage that the spring pressure is applied over a complete 360° circle compared with the substantially limited pressure area or bearing surface of the cross arm 17 if the washer were omitted. This not only increases the total effective pressure at the contact or pressure zone near the edge of the sheet perforations but results in a stiffening up and balancing of the entire assembly and improvement of the locking effect and vibration free connection of the sheets. Furthermore, the washer will relieve the shell 10 of excessive wear resulting in increased efficiency and prolonged life of the fastener. A similar effect is obtained by combining the spreader and washer into a single unit such as by giving the cross arm 17 the shape of a flange or disc provided with suitable recesses or openings for passing and guiding the prong sections 14b. Such a spreader having a disc shaped flange as shown in greater detail in my above mentioned copending application Serial No. 384,461, is difficult and expensive in manufacture in that it involves a machining operation compared with the simple stamping of a T-shaped spreader shown in Figure 4 of the present application. On the other hand, the latter has the disadvantage as pointed out, especially in a clamp embodying a heavy compression spring, that only a small portion of the spring bears against the narrow spreader cross arm 17, resulting in frequent canting and unbalancing of both the spreader and the entire clamp structure and other drawbacks well understood.

By the use of a simple washer 18 having at least one recess adapted to receive the spreader cross arm as shown and described and which may also be manufactured by a simple stamping operation, there is obtained the equivalent of a flanged spreader with all the attendant advantages thereof as pointed out.

If desired, the lower edge of the washer 18 may be formed with a sharp corner as shown in the drawings at points x in which case the latter will dig in or press against the inner surface of shell 10 thereby preventing rotation of spreader 16-17 by accidental rotation of retainer 14 against the friction between the spring 20 and washer 18. Alternatively, the lower edge of washer 18 may be rounded so as to more nearly conform to the bottom 12 in the same manner

as the spreader portion 17, whereby the spreader may follow the rotation of the retainer 14 provided the force applied is such as to overcome the friction between spring 20 and the upper surface of washer 18.

The outwardly curved or valuted shape of the bottom 12 of shell 10 has the effect that the clamping pressure exerted by spring 20 will be concentrated upon a narrow annular zone near the perforation in the upper skin sheet A opposite to and substantially equal to the contact or pressure area between the shoulders 15 and the adjacent edge zone near the perforation in the lower skin sheet B. In this manner, unnecessary pressure areas outside the effective or clamping zones are avoided, resulting in a smaller clamping spring and a corresponding reduction of the all-over size of a fastener designed for holes of a given diameter and a predetermined clamping force. The latter is determined by the fact found from experience, that for $\frac{1}{8}$ " holes it should have such a value that no less than 16 lbs. are required to separate a combination sheet thickness of $\frac{1}{16}$ ", or no less than about 35 lbs. to separate a combination sheet thickness of $\frac{1}{8}$ " to maintain a perfect and vibration free connection of the sheets or other members during a riveting operation. This minimum clamping force and the necessary size of the spring being therefore a given quantity, it has been the object and purpose of the invention to provide a construction of a skin fastener which, while complying with the above requirements, results in a device of smallest possible size and bulk, and which, nevertheless, is most efficient and durable even after extended use and can be applied to and withdrawn from the perforations in the sheets or other member to be clamped in a quick and simple manner in addition to other advantageous features described and apparent from the remaining parts of the specification.

An alternative construction for providing a concentrated pressure area near the perforations is shown in Figures 5, 6 and 7. According to the latter I provide an additional flanged sleeve element having a cylindrical portion 27 and a flange or annular portion 28 (see Figure 6), said cylindrical portion being inserted in the perforation 13 in the bottom 12 which latter in this case may be flat instead of curved, and said flange 28 resting against the inner wall of bottom 12 and being in turn engaged by the spreader portion 17 and inverted cupped washer 18 in substantially the same manner as shown in Figure 1. It will be understood that in this case the inner diameter of the sleeve 27 should be substantially equal to the diameter of the holes in the sheets A and B or, in other words, that it should conform substantially to the diameter of the combined cross-section of the spreader portion 16 and prong sections 14c. Prong 14, cap 21, washer 18, and spreader 16, 17 form a complete self-contained subassembly and in order to hold this subassembly in the body or shell 10, depressions or indentations 30 (see Figure 6) are applied to the outer part of the shell close to the upper edge of the washer 18. These depressions which may take the form of a continuous groove serve to retain the washer 18 and spreader 16, 17 in the shell 10 and may be applied after the washer has been placed in position or previously in which case the washer is placed in position by pressure to pass the indentations 30 with a snap action.

An important advantage of the fastener de-

scribed hereinabove is the fact that it can be readily and easily assembled and dis-assembled by unskilled labor. Thus, for assembly, the retainer 14 is passed through the opening in the washer 18 and the spreader 16, 17 is then inserted between the prongs of the retainer so that spreader portion 17 equally projects from the opposite sides of the prongs and engages the recesses in the cylindrical portion of the washer 18. This sub-assembly is then dropped in the shell 10 so that the washer and spreader will rest against the inner surface of the bottom 12 of the shell. Spring 20 is then placed around the retainer 14 to engage washer 18 and cap 21 applied to the outer bend 14d of the spring which is then compressed in a suitable jig or by means of a suitable skin fastener plier so that the upper bent portion 14d aligns with the diametrical perforation in the cap to enable cross-pin 24 and locking ring 25 to be placed in position. Upon subsequent release of spring 20, the retainer 14 will be moved in an upward direction until shoulders 15 camming over the suitably curved end of the spreader 16 and spread apart by the latter will engage the undersurface of the bottom 12 adjacent to the opening 13 thereby holding the fastener in assembled condition.

In order to apply the fastener to the holes of two or more skin sheets or other structures, such as sheets A and B shown in the drawings, the same is compressed by the aid of a suitable applicator or plier which may be of standard or preferably of the improved construction according to the invention and described in the following with reference to Figures 8 and 11. In the compressed position the prong sections 14c and shoulders 15 passing beyond the spreader are operated towards each other as shown in Figure 8 so as to enable their insertion through the holes in the sheets A and B until the bottom 12 of shell 10 rests against the upper skin sheet A as shown in Figure 8. Upon release of the plier pressure the retainer will be drawn against the shell causing a clamping of sheets A and B along the narrow pressure zones of the bottom 12 and the shoulders 15 in substantially the same way as during the assembly of the fastener.

For disassembly, cap 21 is again compressed towards cup 10 by means of a plier or in a special jig. In this position ring 25 and pin 24 may be removed, enabling a withdrawal of cap 21 and resulting in expansion of spring 20 to its uncompressed condition. Spreader portion 16 is then pushed into the cup so as to cause shoulders 15 to approach each other and allow of withdrawal of prong 14 through the opening 13.

The plier shown in Figure 8 has an upper jaw 31 adapted to engage the top of cap 21 and a lower bifurcated jaw 32 engaging the underside of flange 11 of the shell 10, said jaws being pivoted at 33 in a manner well understood. An isometric view of the plier is shown in Figure 9. The improvement according to the invention resides in the provision of a recess 34 in the upper jaw 31 adapted to engage the tapering cap 21 of the fastener, said recess having a taper somewhat less than said cap to secure a slight wedging effect and spacing of the curved upper surface 22 of cap 21 from the inner surface of said recess 34 as shown more clearly in Figure 10. In this manner, the fastener is prevented from slipping or twisting during compression of the spring 20, thereby greatly adding to its reliability and safety during use. In order to further increase this advantage, the lower bifurcated jaw 32

32 of the plier is provided with an annular recess 35 adapted to receive the flange 11 of shell 10, thus insuring a perfect alignment and balance of the fastener in the plier and greatly facilitating the application to and removal thereof from the sheets A and B.

Referring to Figures 12 and 13, I have shown a few modified designs of the shell 10 of a skin fastener according to the invention especially suited for fasteners designed for use in connection with flush rivets for press or machine counter-sunk sheets A' and B' compared with the standard rivet perforations of sheets A and B as shown in Figure 14. These designs comprise 15 a spherical or conical projection 36 and 37 (Figures 12 and 13, respectively) from the bottom 12 adapted to engage the counter-sunk rivet holes to properly align and centralize the fastener in the inserted position. This type of design furthermore reduces the amount of over-hang projection of the prongs of the retainer 14 and the spreader portion 16, thus making the fastener more rigid and safe for counter-sunk rivet applications.

Finally, I have shown in Figure 15 a modified shell construction having a depending cylindrical flange 38 extending from the opening in the bottom 12, said flange being integral with the shell 10 and taking the place of the separate flanged sleeve 27, 28 of Figures 5 and 7 to obtain a pressure concentration near the holes or perforations of sheets A and B in the manner described. The design of the fastener may otherwise be similar to that shown in Figures 5 to 7. 35 This modification has the advantage of eliminating the indentations or depressions 39 in the shell 10 thereby facilitating the assembly and disassembly of the fastener.

As will be evident from the foregoing, there is 40 provided by the invention a temporary rivet or skin fastener especially, although not limitatively, suited to hold superposed sheets and other structures securely in position for riveting and in such a manner that the vibrations caused by the riveting operations will not loosen the fasteners, while at the same time allowing the fasteners to be easily installed and removed from the sheets. The fasteners completely fill the skin sheet holes by a slight wedge action and are 45 well balanced in the inserted position, thereby holding the sheets in perfect alignment in a tight and substantially vibration-proof grip. Moreover, the coiled tension spring automatically compensates for varying sheet thickness. A still 50 further advantage of the fastener according to the invention is due to the straight line simple assembly, making it possible to carry out easy repairs when after long use interchange of parts may be required. This results in a substantial saving of both time and material. With a 55 standard or special skin fastener plier for compressing the tension spring the fasteners can be easily disassembled and reassembled without special tools.

According to a further feature of the invention, the parts of the shell 10 mostly liable to wear out, such as the flange 11 and bottom 12, are subjected to a localized hardening process by heating the same by means of an electric induction heating coil and subsequent cooling or quenching in oil or the equivalent. In this manner, these parts, i. e., the perforation 13 subject to friction with the prongs and flange 11 which has to withstand the pressure of the plier or other tool, will have the required strength

while the rest of the shell 10 will have a relative softness assisting in maintaining a slightly flexible and well balanced assembly. The degree of hardness of bottom 12 may be chosen sufficiently high to substantially reduce the wear on the edge of the perforation 13 after repeated operation of the fastener while at the same time preventing, during the short period that the fastener is applied, deformation of the sheets if the latter are of a substantially softer metal or metal alloy than the hardened parts.

While I have shown and described a few desirable embodiments of the invention, it is understood that this disclosure is for the purpose of illustration and that various changes in shape, proportion and arrangement of parts as well as the substitution of equivalent elements for those herein shown and described may be made without departing from the spirit and scope of the invention as set forth in the appended claims.

I claim:

1. A clamp for temporarily assembling perforated members comprising a body having an end wall provided with an opening, a retainer having a pair of resilient legs slidable through said opening and provided with shoulders at the outer ends thereof, a T-shaped spreader having a cross arm and a depending portion, said cross arm bearing against the inner surface of said end wall and said depending portion projecting through said opening and being interposed between said legs to form therewith a cross-sectional area of a diameter substantially equal to the diameter of the perforations in the members to be clamped, an inverted cupped washer having a flat portion overlying said cross arm and a cylindrical flange provided with diametrical recesses, the ends of said cross arm engaging said recesses, and a coil spring encircling said retainer having one end engaging the inner end of said retainer and having its other end engaging said washer, whereby to draw said legs inwardly of said body and to clamp the perforated members between said shoulders and the outer surface of said end wall, said legs upon compression of said spring to force said retainer outwardly of said body projecting beyond said depending portion and being operable towards each other to enable insertion through and removal from the perforations in said members.

2. A clamp for temporarily assembling perforated members comprising a body having an end wall provided with an opening, a retainer comprising a pair of resilient legs, said legs having inner parallel portions and free end portions provided with shoulders and each bent angularly towards the other, a spreader in relative fixed relation to said body having a depending portion projecting through said opening and interposed between said legs to form therewith a cross-sectional area of a diameter equal to the diameter of the perforations in the members to be clamped, and spring means interposed between the inner end of said retainer and said body to draw said legs inwardly of said body and to clamp the perforated members between said shoulders and said end wall, the angularly bent end portion of each of said legs having a length approximately of the order whereby the apex of said angle of bend is positioned near the inner surface of said end wall in the retracted position of said retainer.

3. A clamp for temporarily assembling perforated members comprising a body having an end wall provided with an opening, a retainer slid-

able through said opening having a pair of resilient legs, said legs having inner parallel portions and free end portions provided with shoulders and each bent angularly towards the other to normally leave a predetermined spacing therebetween, a spreader having a cross arm bearing against the inner surface of said end wall and a depending portion projecting through said opening and interposed between said legs to form therewith a cross-sectional area of a diameter equal to the diameter of the perforations in the members to be clamped, and a coil spring encircling said retainer having one end engaging the inner end of said retainer and having its other end arranged to resiliently maintain said spreader in bearing engagement with said end wall, whereby to draw said legs inwardly of said body and to clamp the perforated members between said shoulders and outer surface of said end wall, the angularly bent end portion of each of said legs having a length substantially of the order, whereby the apex of said angle of bend is positioned near the inner surface of said end wall in the retracted position of said retainer.

4. A clamp for temporarily assembling superposed perforated members comprising a sleeve having an inner diameter equal to the diameter of the perforations in the members to be clamped and provided with a flange at its inner end, a retainer comprising a pair of resilient legs slidable through said sleeve and provided with shoulders at the outer ends thereof, a T-shaped spreader having a cross arm bearing against the inner surface of said flange and a depending portion projecting through said sleeve and interposed between said legs to form therewith a cross-sectional area of a diameter equal to the inner sleeve diameter, a cupped washer having diametrical recesses overlying said cross arm, the ends of said cross arm engaging said recesses, and a coil spring encircling said retainer having one end engaging the inner end of said retainer and having its other end engaging said washer, to draw said legs inwardly of said sleeve and to clamp the perforated members between said shoulders and the outer edge of said sleeve.

5. A clamp for temporarily assembling perforated members comprising a body having an end wall provided with an opening, a retainer having a pair of resilient legs slidable through said opening and provided with shoulders at the outer ends thereof, a T-shaped spreader having a cross arm and a depending portion, said cross arm bearing against the inner surface of said end wall and said depending portion projecting through said opening and interposed between said legs to form therewith a cross-sectional area of a diameter substantially equal to the diameter of the perforations in the members to be clamped, a washer overlying said cross arm, said washer having at least one recess adapted to receive and to lock said cross arm with respect to said washer, and a coil spring encircling said retainer and having its other end engaging said washer, whereby to draw said legs inwardly of said body and to clamp the perforated members between said shoulders and the outer surface of said end wall, said legs upon compression of said spring to force said retainer outwardly of said body projecting beyond said depending portion and being operable towards each other to enable insertion through and removal from the perforations in said members.
